UNITED STATES PATENT OFFICE.

PETER F. BESSY, OF WHITING, INDIANA.

MAGNETO.

1,361,436.

Specification of Letters Patent. Patented Dec. 7, 1920.

Application filed December 3, 1918. Serial No. 265,125.

To all whom it may concern:

Be it known that I, PETER F. BESSY, a citizen of the Republic of France, residing at Whiting, Indiana, have invented certain new and useful Improvements in Magnetos, of which the following is a specification.

My present invention relates to improvements in magnetos designed for the ignition of internal combustion engines and more particularly to magnetos of the type employing a stationary winding permanently connected to the circuit and in which current is induced through the coaction of relatively stationary field magnets and rotors or inductors.

I have aimed to provide an extremely simple, economical, durable and efficient form of magneto embodying a casing comprising a plurality of parts readily assembled and disassembled in manufacture and repair.

I have further aimed to provide a casing supported from a cradle on ball bearings so that the advance and retardation of the spark may be effected by the rocking of the magneto casing as a whole.

Another object is to provide a construction which may be readily changed for rotation in either direction without changing any of the parts.

Again I have aimed to provide a form of housing of novel shape carrying the breaker or interrupter and the distributor, the moving parts of which may be driven from the magneto shaft through bevel or worm gears.

I have further aimed to provide pole pieces of improved form; and an improved form of breaker or interrupter and cover therefor embodying a safety lock.

With these and other objects in view which will hereinafter appear, the invention includes the novel features of construction and arrangement and combination of parts hereinafter described and defined by the appended claims.

An embodiment of my invention is illustrated in the accompanying drawings in which:

Figure 1 is a central longitudinal section through the magneto.

Fig. 2 is a section on line 2—2 of Fig. 1.

Fig. 3 is a section on line 3—3 of Fig. 1.

Fig. 4 is a diagrammatic view illustrating the circuits.

Fig. 5 is a plan view of the breaker or

interrupter, the breaker cover being removed.

Fig. 6 is a detail view of the breaker or interrupter.

Fig. 7 is an inside view of the breaker cover showing the safety lock.

Fig. 8 is a detail of the distributor, and,

Fig. 9 is a perspective detail of one of the pole pieces.

Referring by reference characters to this drawing, the numeral 1 designates a cradle or frame having a suitable base portion designed to be secured in any convenient manner and which is provided at each end with upstanding portions provided with cylindrical bearing portions indicated at 1^a, the upper halves of the bearing portions being removable for convenience of assembly.

The numeral 2 designates the magneto casing as a whole which comprises four parts, to wit, a main portion 2^a carrying the field magnet or magnets and pole pieces, a portion 2^b carrying the breaker and distributor and condenser, and the end caps 2^c and 2^d respectively. These respective parts are provided with interlocking edges as clearly shown in Fig. 1 so that when assembled they are held in proper relation and alinement and the end caps are provided with extensions, 3 and 5, which are mounted to oscillate in the bearing portion 1^a of the cradle.

The casing is preferably constructed of brass and I find it desirable to form the extension 3 in the shape of a steel ring having annular flanges 3^a resting in an annular channel or rabbet in the end cap and secured in position by screws 3^b.

Interposed between cylindrical extension 3 and the bearing portion 1^a of the cradle as an anti-friction bearing which may conveniently comprise inner and outer bearing rings 4 and 4^a and the edged or spaced balls 4^b.

The extension 5 may be in the shape of a solid cylinder or boss carried by a plate or disk 5^a set into a recess in the end cap and secured in place by set screws, anti-friction rings and balls being interposed between this boss and the bearing portion of the cradle.

The magneto shaft is designated 6 and is rotatably mounted within and supported by the end caps through the interposed ball bearings 7.

The shaft is projected at one end through the cylindrical boss or extension 3 and is provided with means for attachment of a drive gear or the like (not shown) such

5 means being shown as a tapered portion 6^a and screw threaded extension 6^b. The bearings at either end may be protected by dust caps 8.

Pinned or otherwise secured to the shaft 10 within the portion 2^a of the casing are a pair of diametrically arranged rotors 9 which have cylindrical core extensions 10 extending toward each other which revolve within the stationary winding 11. These 15 rotors coact with the pole pieces 12 of the magneto which preferably comprise two pairs of inner and outer magnets as shown in Figs. 1 and 2. The pole pieces are set in openings formed in opposite sides of the 20 casing portion 2^a and may be conveniently secured therein by casting said portion around the pole pieces, and the arms of the magnets are secured to the pole pieces by screws as shown in Fig. 2 or by any other 25 convenient means.

Each pole piece, as shown in Fig. 9, comprises a pair of end portions 12^a thickened and curved on their inner faces to conform to the path of rotation of the rotors, and 30 a connecting web 12^b.

The winding 11 as above stated is stationary, and comprises an inner primary coil or winding 11^b and an outer secondary winding 11^c inclosed within an insulated casing 35 11^a, one end of the primary coil being grounded and the other end being connected to the interrupter and condenser 13 as indicated in the diagrammatic view Fig. 4, in which the heavy line indicates the primary winding.

The secondary coil or winding 11^c is connected to the primary winding and to the distributor indicated at 14 from which the current is conveyed to the spark plugs in 40 the customary manner.

I prefer to secure to the end of the secondary winding 11^c a copper strip 11^d which contacts with the carbon contact 15 seated in an opening in the insulating casing 11^a. 45 This insulated casing is provided with a boss or projection 11^x having an inclined wall which is engaged by the flaring mouth of a tubular insulating bushing or sleeve 16 which passes through an opening in the 50 magneto casing and is held in position by a spring arm 17 pivotally connected at one end to the casing by screw 18 and having a laterally disposed forked portion at the opposite end adapted to overlie a shoulder 55 16^a on the bushing 16. By swinging the spring arm 17 laterally the bushing may be removed. The screw 18 may also serve as the ground connection for the primary winding.

60 55 The bushing 16 carries a binding post 18'

having a tubular bore at its lower end within which is slidably mounted a second carbon contact 19 which is pressed downwardly by a spring 20.

The binding post is connected to the conductor leading to the distributor in any approved manner. To provide a safety gap in case any spark plug is inactive I connect to the binding post a spring contact arm 21 the free end of which bears against the 70 head of a contact member 22 preferably removably seated in an opening in an insulator cap or bushing 23 carried by an annular flange 24 on the magneto casing, a part of the wall is cut away for ventilation 75 purposes and is covered by reticulated material 24^a of sufficient fineness to prevent ignition of any gasoline vapors that might surround the magneto. The lower end of the contact member 22 is provided with 80 spark points or terminals properly spaced from the head of a screw 25 set into the casing, the head of the screw being cross grooved to provide coating points.

The casing portion 2^b is provided with two 90 cylindrical extensions 2^x and 2^y designed to carry the breaker and distributor respectively and the wall of the casing is shaped to provide bearings for the breaker shaft 13^a and distributor shaft 14^a. These shafts 95 I preferably arrange in the same plane transversely of the casing and they rotate on axes that converge in the axis of the main drive shaft 6.

One of these shafts (13^a) has a bevel gear 100 26 fast on its lower end which meshes with a bevel gear 27 on the magneto shaft 6.

Shaft 13^a carries a second bevel gear 28 which meshes with a bevel gear 29 on the shaft 14^a.

105

These shafts 13^a and 14^a are preferably journaled in suitable bushings as clearly shown in Fig. 3.

Within the bottom of the chamber formed by the annular wall or extension 2^x is located the breaker disk 30 which is of ring form as shown in Figs. 3 and 5, and is removably held in position by the spring ring 31.

The breaker arm 32 is pivoted to the post 115 33 carried by the ring and contacts at its opposite or free end with the adjustable contact screw 34 carried by a lug 35^a of the arc shaped bar 35 secured to the breaker plate but insulated therefrom. The opposite end 120 of the bar 35 is provided with a vertical tubular projection 35^b which carries a sliding contact plunger 36 projecting through an insulating sleeve in the breaker disk and designed to contact with a contact screw 37 125 which passes through the magneto casing and to which the magneto wiring is connected as indicated in Fig. 6. The intermediate portion of the breaker arm is designed to coat with the cam 38 carried by 130

the shaft 13^a, in the usual manner, and the breaker arm is pressed toward the contact screw 34 by a spring 39, one end of which is secured to the breaker arm while its other 5 end bears against a fixed post or pin 40.

The contact plunger 36 is forced downward by a spring 41 and this spring also acts at its upper end on the lower end of a sliding contact 42 held in the upper end of tubular projection 35^b. This sliding contact 42 is designed to coact with a contact member 43 on the breaker cover 44, being provided with a binding post 45 designed to be connected by a wire (not shown) with the usual 10 short circuiting switch on the dash of the automobile. My improved breaker housing cover is designed as a safety cover and is arranged so as to enable the magneto to be locked on the housing in short circuited 15 position.

To this end I provide the cover with a radially movable locking pin 46 designed to engage an opening or recess in the corresponding portion of the breaker housing 25 which pin is normally pressed inward out of engagement with said recess by a spring 46^a. A cross bar or yoke 47 is swiveled to the inner side of the cover and is provided with a pin 47^a designed to be acted upon by 30 a lug or projection 48^a on the lock barrel 48.

The yoke 47 has a cam shaped end designed to coact with the head of the locking pin and force the latter outward into locking position as shown in Fig. 7 and when in 35 this position the opposite end of the yoke contacts with the post 43, thus short circuiting the magneto and preventing driving of the car.

The distributor *per se* may be of the ordinary or any desired construction and as 40 these are well understood by those skilled in the art specific description thereof herein is deemed unnecessary.

It may be noted that by my arrangement 45 of breaker and distributor on the casing section and the manner of driving them I can readily adapt the magneto to engines of any number of cylinders.

In the drawing I have shown it as adapted 50 for a four cylinder engine, but if it be desired for a six cylinder, for example, it is only necessary to substitute a casing section 2^b having the breaker and distributor shafts at a greater angle and enabling the use of 55 the proper larger sized gear on the distributor shaft.

I preferably provide a dust cover 46' for 60 excluding dust from the key opening when the key is removed, which cover may be in the form of a key or plate pivoted on the binding post 45 and provided with a knob or projection 46'' for operating it.

Having thus described my invention, what 65 I claim is:

1. In a magneto, a casing comprising a

pair of substantially cylindrical members having interlocking edges, end plates removably engaging said members, a magnet and pole pieces carried by one of said cylindrical members, a shaft journaled in the end 70 plates and projecting beyond the same, rotors on said shaft cooperating with said pole pieces, a stationary winding encircling the shaft between said rotors, and breaker and distributor mechanisms carried by the other 75 cylindrical member, means for driving said mechanisms from said shaft, and a cradle having bearing portions supporting the projecting ends of said shaft and abutting against the end plates to hold the magnetic 80 casing and end plates together.

2. In a magneto, a casing carrying a field magnet, a main shaft journaled in said casing and carrying current generating means 85 cooperating with said field magnets, radially arranged shafts journaled in said casing, gearing driving said radial shafts from said main shaft, and breaker and distributor mechanism operated from said radial shafts.

3. In a magneto, a casing carrying a field magnet, a main shaft journaled in said casing and carrying current generating means 90 cooperating with said field magnets, radially arranged breaker and distributor shafts journaled in said casing, gearing interposed 95 between said main and breaker shafts, and gearing interposed between said breaker and distributor shafts.

4. In a magneto, a multiple part casing having one part detachably and reversibly 100 connected to another part, one of said parts carrying the current generating means, a main shaft journaled in said casing and having a drive gear within said reversible casing part, breaker and distributor shafts 105 carried by said last named casing part, gearing connecting said breaker and distributor shafts, one of said shafts carrying a gear meshing with the gear on the main shaft.

5. In a magneto, a multipart casing having one part detachably and reversibly connected to another part, one part carrying the current generating means, said reversible part carrying angularly arranged cylindrical projections constituting breaker and 110 distributor housings, interconnected breaker and distributor shafts journaled in said interchangeable casing part, a main shaft journaled in the casing and carrying the 115 rotor of the magneto, a gear on said main shaft, and a gear on the breaker shaft engaging said gear on the main shaft.

6. In a magneto, a casing carrying a breaker housing, an insulated binding post passing through an opening in the wall of 120 said casing, a breaker plate detachably held in said housing, an insulated breaker contact member carried by said breaker plate, said member having a hollow part, a slideable contact member in said tubular part adapted to 125 130

make contact with said binding post, and a spring in said tubular part bearing on said slideable member.

7. In a magneto, a breaker housing, a cover therefor, a lock for fastening said cover on, and means operated by the key of the lock for short circuiting the magneto.

8. In a magneto, a breaker housing, a cover therefor, one of said parts having an annular flange overlapping the other, a radially movable locking pin adapted to be passed through alining openings in said overlapping parts, a cam bar for operating said locking pin, said cam bar having a part adapted to short circuit the magneto when the cover is locked, and key controlled means for operating said cam bar.

9. In a magneto, a breaker housing, a safety cover therefor, key controlled means for simultaneously locking said cover and short circuiting the magneto, and a removable dust protector for covering the key opening.

10. In a magneto, a casing carrying a breaker housing, a binding post carried by said casing, a breaker plate removably held in said housing, a spring pressed contact member supported from said breaker plate adapted to make electric connection with said binding post when the breaker plate is in place, a second spring pressed contact supported from said breaker plate and electrically connected with said first named contact, and a cover for the housing having a binding post for making electrical connection with said last named contact.

11. In a magneto, a magneto casing, and field magnets carried thereby, a shaft journaled in said casing, rotors carried by said shaft, a winding encircling the shaft, be-

tween the rotors, an insulating casing enclosing said winding, an insulating plug passing through an opening in the magneto casing and having a part interlocking with a part on said insulating casing, and means within said plug for connecting the winding to the distributor.

12. In a magneto, a magneto casing, and field magnets carried thereby, a shaft journaled in said casing, rotors carried by said shaft, a winding encircling the shaft between the rotors, an insulating casing enclosing said winding, said insulating casing having an aperture and an annular projection, a contact for the winding seated in said aperture, a tubular insulating plug removably held in an opening in the magneto casing, a binding post carried by said insulating plug and having a hollow lower end, and a spring pressed contact member in said lower end adapted to make electrical connection with said first named contact.

13. In a magneto, a magneto casing, and field magnets carried thereby, a shaft journaled in said casing, rotors carried by said shaft, a winding encircling the shaft, between the rotors, an insulating casing enclosing said winding, an insulating plug passing through an opening in the magneto casing and having a part interlocking with a part on said insulating casing, and means within said plug for connecting the winding to the distributor, a safety gap device carried by the casing adjacent said plug, and a contact arm carried by the plug and electrically connected with said safety gap device.

In testimony whereof, I affix my signature.

PETER F. BESSY.
